CABLE

Howard H. Weber, Rome, N. Y., assignor to General Cable Corporation, New York, N. Y., a corporation of New Jersey

Application June 20, 1930, Serial No. 462,458

9 Claims. (Cl. 173—267)

The present invention relates to improvements in insulated electrical conductors.

In the distribution of electrical energy between consumer's premises and trunk cables on poles, 5 a type of cable is used which is known as "service" cable. Ordinarily, this cable is formed of a plurality of twisted insulated conductors which may be housed in a fibrous jacket and the valleys filled with fibrous strands. Due to the relatively low 10 insulating value of the covering of such cable, it has been necessary, heretofore, to run the cable aerially from the pole to a point on the consumer's premises and then directly into the attic or down into the ground through a conduit and 15 into the cellar. Generally, it is preferable to enter the premises through the cellar but the cost of the necessary conduit and the labor charges for installation have been prohibitive to the average consumer.

20 Among the objects of the present invention, therefore, is the provision of a cable which meets the above conditions, as well as others enumerated in the following specification; that is to say, an inexpensive, flexible cable of relatively high dielectric strength and exceedingly rugged construction, which may be installed aerially or underground from an adjacent pole to the consumer's premises without the usual protective conduit. It is understood that while this invention 25 has been developed for use in connection with "service" cable, it readily lends itself to a variety of other applications, as will be apparent to those skilled in the art.

Other objects of the invention will be apparent 30 from the following specification, wherein a preferred and illustrative embodiment of the invention has been selected for description. In the accompanying drawing—

The single figure of the drawing shows a short 35 section of insulated conductor, wherein the several protective sheaths or jackets are progressively removed to illustrate the entire construction and assembly thereof.

Referring to the preferred and illustrative embodiment of the invention shown in the single 40 figure of the drawing, a pair of metallic conductors 1 and 2 are covered with an insulating compound 3 preferably of vulcanized rubber, and a third metallic conductor 4, which conveniently 45 serves as a ground return conductor, is provided with a fibrous jacket 5. This jacket may conveniently comprise a paper wrapping 6 and a braided covering 7. Each of the rubber-covered conductors is provided with a fibrous jacket 8 which has incorporated therein a suitable mois-

ture-proofing compound, and a similar compound may be applied to the jacket 5 covering the ground return conductor 4. The conductors thus covered are assembled together. If desired, the valleys between the conductors may be partially or entirely filled with jute strands 9 which have been pressure impregnated with a suitable waterproofing compound.

Conveniently, the assembled conductors are covered with a coating 10 of a migratory putty 10 or compound, a sufficient amount being applied so as to complete the filling of the valleys between the conductors, or, in the event that the filler strands 9 are not used, to completely fill the valleys. This caulking compound is preferably 15 formed of a base of a fatty acid pitch, such as stearin pitch, and a mineral filler, such as a short fiber silicate of magnesia, as set forth in the co-pending application of Frank M. Potter, Serial No. 251,767, filed February 4, 1928 and patented April 18, 1933 No. 1,904,527. The magnesium silicate, which is in a finely divided state, is added to the pitch in the amount required to give the desired consistency, which, preferably, at normal atmospheric temperatures, is about like glazing putty, and at 300° F. about like cold molasses. The amount of magnesium silicate added varies with the consistency of the pitch but it is between 10% and 20% of the whole. If a putty of a higher viscosity is desired, fibre asbestos may also be added 20 to the magnesium silicate as a filler. Other mineral fillers, such as alumina, ground quartz, mica or magnesium oxide may be substituted for the magnesium silicate if desired.

The resultant compound is extremely resistant 35 to heat and to oxidation, inasmuch as each individual substance is almost completely oxidized before being combined. Moreover, this oxidation- and moisture-resistant putty does not become brittle in cold weather nor unduly soft in 40 hot weather. It is also noted that since the putty maintains its fluidity, it follows that it tends to flow toward and heal or seal any bruise or rupture which may later be made to the adjacent conductor coverings.

Preferably, sealing or barrier means 11 is positioned around the coating 10 of putty. This means may take the form of a sheath of relatively thin crimped or crepe paper. Conveniently, one or more sheets of such paper are applied 50 longitudinally, with adjacent side edges overlapping. In this way, the putty is maintained immediately adjacent to the separately insulated conductors and in the valleys therebetween, and outward migration of the putty is prevented.

Preferably, the assembled conductors are afforded additional mechanical protection by means of a flexible metallic armor 12, which may take the form of a spiral wrapping of metallic tape, wherein the side edges of adjacent convolutions are interlocked. Conveniently, the outer surface of the metallic armor 12 is covered with a coating 13 of the oxidation- and moisture-resistant compound. This coating, by reason of its migratory characteristic, tends to seal the line of connection between the side edges of adjacent convolutions of the metallic tape. At the same time, the putty protects the metallic armor 12 from corrosion since it covers the outer surface thereof and seals the same from moisture.

In order to prevent the outward migration of the putty coating 13, barrier or sealing means 14 is provided, which is similar to that at 11, being formed conveniently of a plurality of longitudinal wrappings of relatively thin crepe paper positioned so that the side edges thereof overlap. The cable thus constructed is preferably provided with an outer protective jacket 15, such as a fabric braid provided with a waterproofing saturant of, say, soft wax.

Preferably, a tough, skin-like covering 16 is positioned over the outer braid 15. This covering may comprise a coating of paint, such as is disclosed in the aforesaid application. As therein stated, the paint may be formed of a metallic oxide, such as red iron oxide, litharge, alumina, magnesium oxide, etc. This metallic oxide is mixed with a specially prepared oxidizable oil which may include boiled linseed oil, partially polymerized China-wood oil, stearic acid and zinc resinate.

This paint, when dry, provides a tough, waterproof skin, which is effective to prevent migration of the saturant used in the outer jacket 15. The paint also protects the fibrous jacket 15 from the deteriorating effect of the ultra-violet rays; and the germicide, which is contained in the paint, resists bacterial growth especially in the adjacent fibrous coverings. Weather conditions over a long period of time have substantially no effect on the paint, and it is especially resistant to acids and alkalis, such as are frequently found in the atmosphere. The paint further affords the insulation protection against attacks by insects and the like. If desired, the finished cable may be provided with a coating 17 of paraffin.

It will be observed that the metallic conductors are afforded substantial electrical and mechanical protection, permitting the ready installation of the cable underground without the usual expensive conduit. At the same time, the cable is of relatively inexpensive construction. Hence, the cabling service charges between an adjacent pole trunk cable and the consumer's premises are reduced to a minimum.

Although only one embodiment of the invention has been shown and described herein, it will be understood that the invention may be variously modified and embodied within the scope of the subjoined claims.

I claim:

1. An article of manufacture comprising, in combination, an electrical conductor, and protective means therefor including a metallic armor, a self-sealing oxidation- and moisture-resistant plastic compound, an outer jacket and a tough, waterproofing coating of metallic oxide paint.

2. An article of manufacture comprising in combination an electrical conductor, a cover

therefor, a protective, helically wound metallic armor surrounding said cover, a layer of corrosion-resistant and moistureproof fatty acid pitch plastic coating material closely adhering to and covering said metallic armor, an outer fibrous cover for said coating material, and an impermeable barrier within said fibrous cover and surrounding said coating material to prevent said material from penetrating said outer fibrous cover.

3. An article of manufacture comprising in combination an electrical conductor, a cover therefor, a protective armor comprising a helically wound metallic tape surrounding said cover, a layer of corrosion-resistant and moistureproof fatty acid pitch plastic coating material closely adhering to and covering said metallic armor, an outer fibrous cover over said coating material, and an impermeable paper barrier within said fibrous cover and surrounding said coating material to prevent said material from penetrating said outer fibrous cover.

4. An article of manufacture comprising in combination an electrical conductor, a cover therefor, a layer of corrosion-resistant and moistureproof plastic coating material surrounding said cover, a protective helically wound metallic armor surrounding said coating material, an impermeable barrier between said armor and said coating material for preventing outward migration of said material, a second layer of corrosion-resistant and moistureproof plastic coating material closely adhering to and covering said metallic armor, an outer fibrous cover for said coating material, and an impermeable barrier within said fibrous cover and surrounding said coating material to prevent said material from penetrating said outer fibrous cover.

5. An article of manufacture comprising in combination a plurality of insulated electrical conductors arranged together to form valleys therebetween, strands located in said valleys so as to at least partially fill the same, a layer of corrosion-resistant and moistureproof plastic coating material surrounding said conductors and completing the filling of said valleys, a protective metallic armor surrounding said layer of coating material, a second layer of said coating material closely adhering to and covering said metallic armor, an outer fibrous cover for said coating material, and a tough waterproofing coating of metallic oxide paint surrounding said fibrous cover.

6. An article of manufacture comprising in combination a plurality of insulated electrical conductors arranged together so as to form valleys therebetween, strands located in said valleys so as to at least partially fill the same, a layer of corrosion-resistant and moistureproof plastic coating material surrounding said conductors and completing the filling of said valleys, an impermeable paper barrier surrounding said plastic coating material, a protective metallic armor surrounding said paper barrier, a second layer of corrosion-resistant and moistureproof plastic coating material closely adhering to and covering said metallic armor, an outer fibrous cover for said coating material, and an impermeable barrier within said fibrous cover and surrounding said coating material to prevent said material from penetrating said outer fibrous cover.

7. An article of manufacture comprising, in combination, a plurality of insulated electrical conductors assembled to form valleys therebetween, strands located in said valleys, a layer of insulating material electrically and mechanically

- protecting the assembled conductors, a metallic armor surrounding the conductors and overlying said layer, a layer of moisture-resistant plastic compound surrounding the armored conductors, 5 a barrier of paper impermeable to said compound overlying said last mentioned layer, and a surrounding braided jacket coated with a moisture-resistant compound.
8. An article of manufacture comprising, in combination, an electrical conductor, and protective means therefor including an interlocking, 10 helically wound metallic armor, a layer of moisture-resistant plastic compound and a barrier of paper impermeable to said compound underneath 15 said metallic armor, a second layer of moisture-resistant plastic compound and a second barrier of paper impermeable to said last mentioned com-
- pound over said metallic armor, and an outer braided jacket coated with a moisture-resistant compound.
9. An article of manufacture comprising, in combination, a plurality of insulated electrical conductors assembled to form valleys therebetween, filler material in said valleys, a protective covering over the assembled conductors, an overlapping helically wound metallic armor surrounding the assembled conductors, a protective covering over the metallic armor, a surrounding braided jacket coated with a moisture-resistant compound, and a thin paper barrier between said metallic armor and one of said protective coverings.
